UNITED STATES PATENT OFFICE.

JOHN O. NEIKIRK, OF MORGAN PARK, ILLINOIS, ASSIGNOR TO RODGER BALLAST CAR COMPANY, OF CHICAGO, ILLINOIS, A CORPORATION OF MAINE.

BALLAST-CAR.

1,138,006.

Specification of Letters Patent.

Patented May 4, 1915.

Application filed November 21, 1910. Serial No. 593,300.

To all whom it may concern:

Be it known that I, JOHN O. NEIKIRK, a citizen of the United States, residing at Morgan Park, in the county of Cook and State of Illinois, have invented a certain new and useful Improvement in Ballast-Cars, of which the following is a description, reference being had to the accompanying drawings, which form a part of my specification.

My invention relates to an improvement in ballast cars, having to do more especially with the underframe of a ballast car known as the Hart convertible type of car, the purpose of the invention being to provide a construction of underframe in which the load will be distributed to the load carrying elements in an effective manner.

In the drawings: Figure 1 is a central longitudinal section of a portion of a ballast car with my improvement. Fig. 2 is a horizontal sectional view of the same taken just below the floor of the car with a portion of the longitudinal sills shown in section to more clearly illustrate my invention. Fig. 3 is a transverse sectional view taken on the line *a—a* of Fig. 2 looking in the direction of the arrows. Fig. 4 is a detailed view in perspective of the underframe of the car.

My invention has to do with the construction of the steel underframe of a ballast car and more especially of the Hart convertible type of ballast car as illustrated in the drawings.

As the invention merely relates to the construction of the underframe, the description will be confined to that portion of the car.

In a ballast car of the type referred to and illustrated in the drawings, no longitudinal sill is employed as such a sill would obstruct the flow of material through the hopper. The load carrying members of the car comprise two intermediate, longitudinal sills 1—1, which extend longitudinally of the car adjacent to the hopper 2—2, as can be more clearly seen in Fig. 3, and outside longitudinal or side sills 3—3; all of the longitudinal sills being connected together at, or near, the ends thereof by the usual cross sills or end members 4, and also by the usual bolsters 8—8. The longitudinal sills

are formed as girders, which may be of any suitable construction. As shown, they are formed as plate girders comprising web portion 5 for the intermediate sills and angle irons 6 and 7 riveted to the upper and lower edges of the web portion respectively. The side girders are similarly formed with web portion 8' to which angle irons 9 and 10 are riveted at the upper and lower edges respectively.

As a considerable portion of the load will be carried by the intermediate longitudinal sills 1—1, these sills are preferably made of greater depth than the side sills 3. A portion of the strains on the intermediate longitudinal sills is transmitted to the side sills 3. In order to provide for the effective transmission of strains from the intermediate sills to the side sills, I provide webs 5 of the intermediate sills with openings, or passages, therethrough.

The transverse sills or cross members 11 may be in the shape of a channel iron as illustrated, see Figs. 1 and 4, or of any suitable shape having the requisite strength. Where the intermediate sills are constructed as illustrated in the drawings, the openings in the webs 5 are preferably made a short distance below the top of the web so as not to interfere with the angle irons 6—6, which constitute the horizontal flange at the upper edge of the intermediate longitudinal sill. The transverse member 11 after being put into position through the openings in the intermediate sills is secured to both intermediate sills and the side sills by the angle irons 12, which are securely riveted to the longitudinal sills and to the transverse sills as clearly illustrated in Figs. 3 and 4. It is apparent that when the intermediate sills are deflected the excess load will be transmitted directly through the continuous cross members to the side sills 3.

I have shown and described one method of employing my invention, but I do not wish to be understood as limiting myself to the exact construction shown, but

What I claim and wish to secure by Letters Patent is:—

In a car under-frame structure, the combination with side sills made up of vertical

web plates and top and bottom reinforcing angles, of vertical joint angles riveted to the said web plates, metallic cross ties riveted to said joint angles, and having continuous 5 end portions that project through the said web plates, and supplemental side sills sup- ported by the projected ends of said cross ties.

J. O. NEIKIRK.
